UNITED STATES PATENT OFFICE.

ADOLPH P. S. WOHLPART AND PHILIP WOHLPART, OF NEW YORK, N. Y.

COOLER.

No. 823,016.

Specification of Letters Patent.

Patented June 12, 1906.

Application filed August 11, 1905, Serial No. 273,757.

To all whom it may concern:

Be it known that we, ADOLPH P. S. WOHLPART and PHILIP WOHLPART, citizens of the United States, and residents of the borough 5 of the Bronx, in the county of New York, city and State of New York, have invented certain new and useful Improvements in Coolers, of which the following is a specification.

Our invention relates to surface-air coolers adapted to be used for the purpose of cooling water employed to reduce the temperature of the cylinders in vehicles propelled by hydrocarbon-engines, and particularly to coolers in which the water is caused to pass 10 through a chamber intersected by numerous tubes through which the air passes, the water being cooled by contact with the outer surfaces of the said tubes. Its objects are, among others, to provide a simple, strong, 15 and durable cooler construction which may be easily constructed and assembled, will afford a maximum cooling-surface, and in which the tubes may be accurately spaced and the spaces between them rendered water-tight at an expenditure of a comparatively 20 small amount of labor and the use of a minimum of materials. It is applicable to various forms of engines, and on account of the efficient cooling of the water and the strong, 25 light, and durable construction of the cooler, it is adapted to be used in connection with engines of the highest speed and horse-power.

It will be readily understood that two of the principal objects to be attained in the 30 construction of coolers of this character are, first, an accurate spacing of the tubes without obstruction of the spaces through which the water passes between said tubes, and, second, such strength and durability as will 35 prevent leakage or displacement of any of the parts. In our construction both of these objects are attained and we are enabled to use air-tubes made of extremely light metal, thus insuring ready transmission of the heat from 40 the water to the cooling-air which passes through said tubes, while at the same time the structure is capable of resisting any ordinary strains or vibrations to which it may be subjected in ordinary use.

To these ends our improvements consist of the construction, combination, and arrangement of parts hereinafter described and claimed, and illustrated in the accompanying drawings.

In the said drawings, Figure 1 is a front

view of a cooler embodying our improvements. Fig. 2 is a vertical cross-section of the same on the line 2-2 in Fig. 1 looking in the direction indicated by the arrow in said figure. Fig. 3 is a horizontal section on the line 3-3 of Fig. 1. Figs. 4, 5, and 6 are enlarged details of detached portions of our preferred construction. Figs. 7, 8, and 9 are similar views of a modification, and Figs. 10, 11, and 12 are similar views of another modification.

The cooler is provided with a cap A' at its top, closing the filling-tube A, through which tube the cooler may be refilled or replenished. This filling-tube communicates with a receiving-tank B, which has an inlet-pipe C at one side, by which the heated water returning from the engine-cylinders enters the cooler. At the lower part of the cooler is a receiving-chamber D, which receives the water after it 75 has passed through the cooler proper. It has a return-pipe E at one side, through which the water passes to the cylinders after being cooled, and it is also provided with a small cock, by means of which the cooler may be emptied when desired.

The air-tubes H are preferably made of thin seamless brass or copper tubing and are of rectangular cross-section; but they may be made of any other suitable material and of other cross-sectional form. They extend through the cooler-frame I from the front to the back and permit air to pass therethrough as the vehicle to which the cooler is attached travels. In placing the said tubes 90 in the frame of the cooler a framework of interlocked wires and strips is first made. This consists of a number of strips J and wires K, the strips being provided at stated intervals with holes through which the wires 95 pass. When this framework is made, the ends of the air-tubes are placed therein, and the said framework and tube ends are then immersed in a solder-bath, so that they are united and all interstices sealed. Another 100 framework is then applied to the opposite ends of the tubes in a similar manner. After this operation is completed the tubes and their framework are then placed in the outer frame and secured therein by soldering or 105 other suitable means. It will be seen that by the use of the framework composed of the wires and strips K and J the spaces to receive the tube ends may be accurately formed and the spaces between the said tubes exactly de- 110

terminated, the latter corresponding to the thickness of the strips and wires, respectively.

In the modification of Figs. 7 to 12 instead of running the wires through holes in the strips mortises are provided.

In the modification of Figs. 7, 8, and 9 there are two strips, each provided with mortises to receive the other, by which means they are securely interlocked.

In the modification of Figs. 10 to 12, inclusive, the strips only are notched or mortised, and the wires are run through these mortises. It will be observed also that other modifications of the structure may be made without affecting the principles of the improvements.

In operation the heated water returning from the cylinders enters the receiving-tank B and then gradually passes down through the spaces between the air-tubes H and is cooled through contact with the surface of the said tubes, finally reaching the tank D at the bottom, from whence it is returned in a cool condition to the said engine-cylinders.

What we claim is—

1. The combination, in a cooler, of an inlet-tube and an outlet-tube, a cooling-compartment intermediate the same consisting of a plurality of parallel open-ended air-

tubes, a framework composed of a plurality of intersecting strips and portions of some of the strips removed to receive other strips.

2. The combination, in a cooler, of an inlet-tube and an outlet-tube, a cooling-compartment intermediate the same consisting of a plurality of parallel open-ended air-tubes, a framework composed of a plurality of strips disposed at angles to each other, the strips disposed in one line having portions removed to receive the strips disposed at an angle thereto.

3. The combination in a cooler of an inlet-tube and an outlet-tube, a cooling-compartment intermediate the same consisting of a plurality of parallel open-ended air-tubes, a framework composed of a plurality of strips arranged in parallel rows, the strips of one row being disposed at an angle to the strips of the other row and each strip having notched portions at its intersections with the strips of the other row.

Witness our hands, this 31st day of July, 1905, at the city of New York, in the county and State of New York.

ADOLPH P. S. WOHLPART.
PHILIP WOHLPART.
